UNITED STATES PATENT OFFICE.

FLOYD D. JONES, OF KANSAS CITY, MISSOURI, ASSIGNOR TO JONES RAZOR AND MANUFACTURING COMPANY, OF KANSAS CITY, MISSOURI, A CORPORATION OF MISSOURI.

SAFETY-RAZOR.

1,081,748.

Specification of Letters Patent. Patented Dec. 16, 1913.

Application filed June 21, 1912. Serial No. 705,103.

To all whom it may concern:

Be it known that I, FLOYD D. JONES, a citizen of the United States, residing at Kansas City, in the county of Jackson and 5 State of Missouri, have invented certain new and useful Improvements in Safety-Razors, of which the following is a specification.

This invention relates to safety razors, and my object is to produce an inexpensive and 10 thoroughly efficient razor of ornate appearance.

Another object is to produce a razor having a frame, a fingered guard, a stiff or rigid blade, a clamp plate for securing the blade 15 in position, and an adjustable wedge for springing the guard away from the cutting edge of the blade.

Another object is to produce a plate for 20 clamping the blade in position and for shielding the cutting corners of the blade irrespective of the position of the latter with 25 reference to the guard.

With the general objects in view, the invention consists in certain novel and peculiar 25 features of construction and organization, as hereinafter described and claimed; and in order that it may be fully understood reference is to be had to the accompanying drawing, in which:

30 Figure 1, is a front view of a safety razor embodying my invention. Fig. 2, is a back view of the same. Fig. 3, is a horizontal section on the line III—III of Fig. 2. Fig. 4, is a side view of the razor. Fig. 5, is a 35 vertical section on the line V—V of Fig. 2. Fig. 6, is a section on the line VI—VI of Fig. 2. Fig. 7, is a sectional perspective of a plate for clamping the blade of the razor in position and for covering the extremities 40 of the cutting edge thereof.

In the said drawing, 1 is a flat plate or frame of rectangular form. A resilient guard arranged at the rear side of frame 1, and preferably formed integral therewith, 45 consists of a pair of arms 2 extending downward from the upper edge of the frame, a longitudinal bar or portion 3 connecting the lower ends of the arms 2, and a plurality of fingers 4 depending from bar 3, said fingers 50 intermediate their length, being bent forward under and spaced some distance from the lower edge of frame 1 as at 5, and then reversely bent so that the front sides of the lower extremities of the fingers shall extend 55 at a slight angle to the front side of frame

1, and said frame is also provided centrally of its length with an ear 6, which extends downwardly and rearwardly from the upper edge of the frame, and secured to said ear is a shank 7 for engagement by a handle 8, 60 a detailed reference to the construction of the handle and its connection with the shank, being omitted, as it forms no essential part of the razor proper.

The arms 2 of the guard at their junction 65 with the bar 3 thereof are bowed outwardly at 9 to provide a pair of alined passages 10, and fitting in said passages are alined wedges 11 formed upon opposite extremities of a slide bar 12, and said slide bar is of 70 semi-cylindrical form in cross section, with its flat side bearing against the frame, as shown clearly in Figs. 5 and 6, and at one end the slide bar is provided with a rearwardly projecting finger piece 13 whereby 75 the slide bar can be easily engaged for the purpose of moving it longitudinally in one direction or the other.

Fitting flatly against the front side of frame 1 is a razor blade 14, the same corresponding in length to the frame and having its cutting edge 15 depending below the lower edge of the frame and terminating slightly above the front extremity of fingers 4 so that lather and shavings may pass back 85 of the cutting edge of the blade into the space inclosed by the latter, bar 3, the frame and fingers, it being noted that from such space the lather and shavings will be instantly dislodged by passage between the 90 fingers, upon vibrating the lower edge of the razor in water.

16 is a clamp plate fitting flatly against the front side of the blade and provided at such side with depending arms 17 which 95 cover the cutting corners of the blade, and provided also with spring arms 18 which bear against the rear side of the frame, as shown clearly in Figs. 2 and 6, the pressure of said spring arms causing the plate to 100 clamp the blade firmly against the frame.

The clamp plate is preferably secured in position by slipping it over the upper edges of the frame and blade, and has a rearwardly-projecting flange 19 at its upper end 105 which engages the upper edge of the frame and thus limits the said slideable adjustment of the clamp plate, it being noted that the arms 18 project from the rear margin of said flange 19, as shown most clearly in 110

Figs. 2 and 6, and that the flange 19 is cut away at 20 to accommodate the ear 6 of the frame.

- To guard against endwise slippage of the clamp plate and to guide the same as it is slid in or out of position, it is provided with rearwardly-projecting end flanges 21, which incidentally overlap the ends of the frame and blade and thus give the ends of the 10 razor a more substantial and attractive appearance; it being noted that said flanges 21 are deep enough to hide from view the edges of the spring arms 18 interposed between the flanges and the arms 2 of the guard.
- 15 To guard against slippage or creepage of the blade toward the fingers of the guard plate, especially when the clamp plate is being secured in position, the blade is provided in its opposite ends with notches or 20 slots 22 to receive protuberances 23 of the frame, as shown in full lines, Fig. 3 and dotted lines, Fig. 2.

The razor is manipulated in the usual manner and if a close shave is desired the 25 wedge bar is slid in the direction indicated by the arrow, Fig. 3, this action resulting in springing the guard rearwardly or away from the blade, so that the cutting edge of the latter may obtain a firmer bearing 30 against the face, it being noted in this action, that the frame, blade and clamp plate remain in fixed relation so that the arms 17 of the clamp plate shall shield the operator from any possibility of being cut by the 35 corners of the blade.

Where an ordinary shave is desired, the wedge bar will occupy the position shown in Figs. 2, 3, 5 and 6, at which time arms 2 bear flatly against the frame, and the forwardly-projecting portion of the fingers are substantially flush with the cutting edge of the blade so that said portions of the fingers shall prevent the blade from applying any material independent pressure on the operator's skin in the shaving operation.

From the above description, it will be apparent that I have produced a safety razor embodying the features of advantage enumerated as desirable in the statement of 50 the object of the invention, and which is susceptible of modification without departing from the principle of construction as defined by the appended claims.

I claim:

- 55 1. A safety razor, comprising a frame, a guard at the back of the frame, having fingers at its lower edge and capable of being sprung back from the lower part of the frame, a blade fitting flatly against the front 60 side of the frame with its cutting edge projecting beyond the lower edge of the same, a plate clamping the blade against the frame and provided with arms extending downward and covering the cutting corners of 65 the blade, and means for springing the lower

portion of the guard back from the lower end of the blade, and a handle rearward of and connected to the frame.

2. A safety razor, comprising a frame, a guard at the back of the frame, having fingers at its lower edge and capable of being sprung back from the lower part of the frame, a blade fitting flatly against the front side of the frame with its cutting edge projecting beyond the lower edge of the same, 70 means whereby slippage or creeping of the blade on the frame is prevented, a plate clamping the blade against the plane and provided with arms extending downward and covering the cutting corners of the 75 blade, and means for springing the lower portion of the guard back from the lower end of the blade, and a handle rearward of and connected to the frame.

80 3. A safety razor, comprising a frame, a guard at the back of the frame, having fingers at its lower edge and capable of being sprung back from the lower part of the frame, a blade fitting flatly against the front side of the frame with its cutting edge projecting beyond the lower edge of the same, 85 means whereby slippage or creeping of the blade on the frame is prevented, a plate clamping the blade against the frame and provided with arms extending downward 90 and covering the cutting corners of the blade; said plate having rearwardly projecting end flanges overlapping the ends of the frame, the blade and the guard, and means for 95 springing the lower portion of the guard 100 back from the frame and cutting edge of the blade, and a handle connected to the frame.

4. A safety razor, comprising a frame, a guard at the back of the frame, having fingers at its lower edge and capable of being 105 sprung back from the lower part of the frame, a blade fitting flatly against the front side of the frame with its cutting edge projecting beyond the lower edge of the same, a plate clamping the blade against the frame 110 and provided with arms extending downward and covering the cutting corners of the blade, a slide bar fitting against the rear side of the frame and adjustable longitudinally thereof and provided with a plurality of 115 wedge portions for engagement with the guard to spring the lower portion of the same back from the frame, and a handle for the razor.

5. A safety razor, comprising a rectangular frame and a guard integrally formed with the frame and consisting of a bar provided at its lower edge with depending teeth and also provided with arms extending upwardly to the upper edge of the frame and 120 provided near their lower ends with alined outwardly-bowed portions, a blade fitting flatly against the front side of the frame with its cutting edge projecting beyond the 125 lower edge of the same, a plate clamping the 130

blade against the frame, a longitudinally extending and adjustable bar having wedge portions interposed between the frame and the inner side of the bowed portions of said arms, and a handle for the razor.

5. 6. A safety razor, comprising a frame, a guard at the back of the frame, having fingers at its lower edge and capable of being sprung back from the lower part of the frame, a blade fitting flatly against the front side of the frame with its cutting edge projecting beyond the lower edge of the same, a plate clamping the blade against the frame, a slide bar fitting against the rear side of the frame and adjustable longitudinally thereof and provided with a plurality of wedge portions for engagement with the guard to spring the lower portion of the same back from the frame, and a handle for the razor.

10. 15. 20. 25. 7. In a safety razor, a combination guard and blade-seat frame, comprising a blade seat portion and a guard portion formed integral with and folded against said blade-seat portion; said guard consisting of a plurality of resilient arms extending from one

edge of said blade-seat portion and a bar connecting the ends of said arms and provided with a plurality of guard fingers extending opposite the other edge of said blade-seat portion.

8. In a safety razor, a rectangular frame and a guard formed integrally with and disposed rearward of the frame; said guard consisting of a plurality of resilient arms 35 extending downwardly from the upper edge of the frame, a bar connecting the lower ends of the arms, and fingers depending from the lower edge of the bar, the fingers being bent to provide lower portions underlying and spaced from the lower edge of the frame and extending at an acute angle therefrom, a blade, means for clamping said blade adjacent said guard, means for springing the arms away from the guard frame, 40 and a handle for the razor.

In testimony whereof I affix my signature, in the presence of two witnesses.

FLOYD D. JONES.
